UNITED STATES PATENT OFFICE.

LOUIS G. RINK, OF CHICAGO, ILLINOIS, ASSIGNOR TO SHARP & SMITH, OF CHICAGO,
ILLINOIS, A CORPORATION OF ILLINOIS.

FORCEPS.

1,288,995.

Specification of Letters Patent. Patented Dec. 24, 1918.

Application filed September 5, 1918. Serial No. 252,679.

To all whom it may concern:

Be it known that I, LOUIS G. RINK, a citizen of the United States, residing at Chicago, in the county of Cook and State 5 of Illinois, have invented a new and useful Improvement in Forceps, of which the following is a specification.

My invention relates to certain new and useful improvements in forceps and is fully 10 described and explained in the specification and shown in the accompanying drawings, in which:

Figure 1 is a plan view; Fig. 2 is a side elevation; Fig. 3 is an end view; Fig. 4 is a 15 section on the line 4 of Fig. 3, and Fig. 5 is a perspective of the locking mechanism.

Referring to the drawings, 6 and 7 are the two pivoted members of the forceps which may be formed as desired at their 20 meeting ends. The novelty of the structure lies in the locking mechanism at the opposite end, and it will, therefore, be understood that the remainder of the device can be modified as is convenient and therefore does 25 not require detailed description.

The member 7 has projected from it, toward the member 6, an arm 8 on the end of which is an integral finger 9 the upper surface of which is beveled at 10. The member 30 6 of the forceps has pivoted to its end an oscillatable arm 11 having a flattened surface 12 upon which rests the end of a spring 13, the opposite end of which serves in the usual manner to separate the two members of the forceps. By this means the pivoted arm 11 is held in normal position and yet can yield in either direction. The arm 11 has on one 35 face a series of ratchet teeth 13 with any of which the finger 9 can engage. The last 40 of these teeth projects beyond the main portion of the arm 11, and the lateral part of the arm is cut away forming a beveled face or shoulder 14 on the rear of the ratchet.

The operation is as follows:

As the forceps are pressed together the 45 finger 9 on the arm 8 runs over the point of the pivoted arm 11, presses the ratchet back and can be engaged with the first notch of the ratchet. Continued pressure will engage 50 the finger with other notches in the ratchet, until finally the maximum pressure causes the finger to run past the end of the ratchet

when the spring returns it to central position and the finger engages with the beveled surface 14 on the rear of the ratchet, pressing 55 the same in the opposite direction so that the forceps are thus released.

The present structure is advantageous because the locking mechanism can be engaged and released with the least possible shock or 60 necessary movement of the forceps as a whole.

I realize that considerable variation is possible in the details of this construction without departing from the spirit of my invention; therefore I do not intend to limit myself to the specific form herein shown and described except as pointed out in the following claims, in which it is my intention 65 to claim all the novelty inherent in the constructions as broadly as is permitted by the state of the art. 70

I claim as new and desire to secure by Letters Patent:—

1. A forceps comprising two pivoted members, a ratchet device pivoted to one member, a pawl device secured to the other member, the ratchet device being provided with a beveled surface on its rear to return the pawl to disengaging position after it has 80 passed by the ratchet, a spring secured to one of said pivoted members and bearing at one end against one of said pivoted members to open the forceps and at its other end on the ratchet device to hold it normally in central 85 position.

2. A forceps comprising two members pivoted together, a ratchet member pivoted to the end of one of said members and oscillatable about an axis longitudinal of said member and engaging a pawl device rigidly carried by the other member and adapted to engage the ratchet device, the ratchet having at its rear a beveled surface to guide the pawl to disengaging position after movement in engaging direction past the inner limit of the ratchet, the pivotal portion of the ratchet being provided with a flattened surface and a spring carried by the pivoted member and adapted to engage said flattened surface to hold the ratchet normally in central position. 90 95

3. A forceps comprising two members pivoted together, an arm pivotally secured to one

and having a flattened portion, a spring bearing at one end on the said arm to hold the same normally in central position and at the other end on the other member to open the 5 forceps, and an arm provided with an integral finger carried by the other member and adapted to be engaged by ratchet teeth,

the pivoted arm having on its rear a curved surface to guide the finger around the rear of the ratchet.

10

In testimony whereof, I have hereunto set my hand this 3rd day of September, 1918.

LOUIS G. RINK.
